UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

CAR UNDERFRAME.

Application filed August 2, 1922. Serial No. 579,221.

To all whom it may concern:

Be it known that I, DONALD S. BARROWS, a citizen of the United States, residing at Rochester, in the county of Monroe and State of New York, have invented certain new and useful Improvements in Car Underframes; and I do hereby declare the following to be a full, clear, and exact description of the invention, such as will enable others skilled in the art to which it appertains to make and use the same.

My invention relates to car underframes for railway cars and more particularly to a strong, reliable and efficient metallic structure adapted to be applied generally to wooden underframe cars to reinforce the underframe thereof so as to adapt said cars for use under modern service conditions.

To this end one of the principal features of the invention, generally stated, is to provide a metallic structure adapted to be used with the underframe of wooden cars, said structure being used to reinforce the car sills and designed to receive the buffing and pulling shocks which are transmitted thereto by the draft rigging.

Particularly stated, the invention consists in providing a car underframe including in combination a backstop member associated with a movable element of the draft rigging and connected to a plurality of members forming the draft sills, the bolster to which said draft sills are connected, and diaphragm means suitably connected by gusset plates to the bolster in the rear thereof for reinforcing the strength value of the several parts comprising the car underframing.

Another object of the invention is to provide a car underframe and reinforcing means therefor involving diaphragm members of simple construction at the rear of the bolster, said members being increased from a relatively shallow depth or cross sectional area from a point adjacent the reinforcing center sill members to a relatively large cross sectional area or depth substantially equal to the height of the bolster and immediately adjacent the rear thereof.

A further object of the present invention is to provide a car underframe including a plurality of gusset plates, some of said plates being arranged to effectively connect the draft members to the bolster forwardly thereof, said gusset plates being arranged adjacent the backstop casting, and other of

said gusset plates serving to unite the reinforcing diaphragm means and bolster at the rear thereof, the uppermost of said last named gusset plates bridging and connecting the diaphragm means and overlying the bolster.

A still further object of the invention resides in the combination with center sill reinforcing members, a top gusset plate bridging and connecting said members at the rear of the bolster, diaphragm reinforcing means formed with an offset portion adapted to receive and fit said gusset plate and having a shoulder portion at the rear thereof connected to the center sill reinforcing members, and bottom gusset plates underlying said diaphragm means and shoulder portion, said bottom gusset plates being connected to the bolster, diaphragm means and center sill reinforcing members.

There are other features of the invention as will be pointed out hereinafter in connection with the detailed description of my invention illustrated in the accompanying drawings in which

Figure 1 is a plan view of my improved construction.

Figure 2 is a central vertical longitudinal sectional view through the construction shown in Figure 1.

Figure 3 is a horizontal sectional view with parts shown in section and broken away, and other parts illustrated in elevation.

Figure 4 is a transverse vertical sectional view on the line 4—4 of Figure 3.

Figure 5 is a transverse vertical sectional view on the line 5—5 of Figure 3.

In the drawings I have illustrated only a portion of the car underframe adjacent the body portion. It is to be understood, however, that the structure is duplicated at the opposite end of the car and that the center sills hereinafter referred to are preferably continuous, the said sills being adapted to extend from end to end of the car. The car underframe preferably includes the usual end sill and associated parts, not shown, but as is well understood by those skilled in the art.

Referring to the drawings in which corresponding reference characters designate similar parts in the several views, the center sills of the car are provided with center sill reinforcing means, said reinforcing means

including spaced angle members or sills 1—1 adapted to be connected to the said center sills of the car underframe. The bolster may be of the usual construction and is 5 formed with upper flanges 2 and lower flanges 3 extending respectively forwardly and rearwardly, as shown. The center sill reinforcing members are connected at their upper ends by a longitudinally disposed tie 10 plate 4, shown in the form of a stiffening channel, the flanges thereof being connected to the inner opposed faces of the reinforcing sills 1 by means of rivets 5. Filler strips or inserts may be utilized, if found necessary, to accommodate the parts to A. R. A. 15 standard measurements, as will be understood.

The draft members or sills are each preferably formed of angle members 6 and 7, the 20 respective vertical flanges thereof being overlapped and united by means of a plurality of rivets 8 extending throughout the length of said members. The horizontal flange 9 of the upper angle member 6 is 25 relatively wide and is preferably connected, by means of a double row of rivets 10, to the horizontal flange of the angle or center sill reinforcing member, the respective vertical flanges of said angle member 6 being spaced 30 further apart than the vertical flanges of the reinforcing sills to provide for the use of modern draft rigging and its associated parts. The horizontal flange 11 of the lower angle member 7 extends outwardly of the 35 draft sills and has connected thereto, by means of rivets 12, the forwardly extending portion of the bottom gusset plate 13, the rear portion of said gusset plate being connected by means of rivets 14 to the bottom flange 40 of the bolster. The horizontal flanges 11 of the angle members 7 are preferably tied together by means of the cross bar extending transversely of the draft sills intermediate the ends of the backstop member, 45 said cross bar being connected to the horizontal flanges 11 by some of the rivets 12, as shown.

The inner ends of the built-up draft sills are connected by means of angle members 50 15 to the bolster, the ends of said draft sills preferably terminating short of the vertical web portion of the bolster, as shown. Rivets 16 unite one arm of the angle member to the adjacent draft sill, the other arm of 55 said angle member being connected to the bolster web by means of rivets 17. The connecting angle members are preferably arranged upon the outside of the draft sills, as shown.

60 Interposed between and connecting the inner ends of the draft sills is a backstop member 18, said member being preferably spaced from the bolster and adapted to receive buffing shocks from a movable element 65 of the draft rigging shown herein as the

yoke 19 of the well known Farlow equipment. A follower member of the draft rigging is indicated by the numeral 20. The backstop casting or member 18 is formed with a front wall portion 21 having a buffing face adapted to receive the buffing shocks through the yoke member, as will be understood. Side walls 22 of the backstop casting are formed integral with the front wall and are designed to be connected to the inner 75 opposed faces of the draft sills and more particularly the overlapped vertical flanges of the respective angle members 6 and 7. Certain of the rivets 8 serve to connect the backstop to the draft sills. The rear wall 80 23 of the casting is united to the front wall by means of vertically and horizontally arranged webs or flanges 24. The horizontal flange or web also unites the side walls of the backstop. The rivets connecting the side 85 walls of the backstop casting to the draft sills extend throughout the length of said side walls and serve to firmly unite the backstop member to the associated angles 6 and 7, certain of said rivets passing through 90 both vertical flanges of the angle members and other of said rivets passing through but the vertical flange of the upper angle member 6.

The means reinforcing and bracing the 95 forward portion of the underframe above described, includes spaced vertical diaphragm members 25, each associated with an adjacent center sill reinforcing member and longitudinally disposed with relation thereto. Each diaphragm member is preferably formed of a Z-bar having at its forward end an outwardly projecting flange 26 adapted to be connected to the rear face of the web of the bolster by means of the rivets 17 hereinbefore referred to as connecting one arm of the angle member 15 to said web. The vertical web portion of each diaphragm member increases in depth from a point at the rear of the bolster adjacent the center 100 sill reinforcing members to the rear edges of the bolster flanges, said web portion extending between the flanges and terminating in the outwardly extending flange 26, as shown. Each diaphragm member is provided with an upper flange 27 connected to the horizontal flange of the center sill reinforcing members by means of rivets 28, said flange being arranged to extend inwardly and having its forward portion offset to 110 underlie the top flange of the bolster, as clearly shown in Figure 2. The rear end of the flange 27 is relatively thickened to form a shoulder recessed portion 29 adapted to receive the top gusset plate 30.

The top gusset plate 30 is interposed between the lower flanges of the center sill reinforcing members and the flanges 27 of the diaphragm member, said gusset plate bridging said members and extending outwardly 130

therefrom suitable distances upon each side of the center sills, as shown. The forward portion of the gusset plate 30 is adapted to overlie the bolster and is connected to the 5 top flange thereof by means of a plurality of rivets 31 arranged upon the respective sides of the web portion of said bolster. The rear portion of the gusset plate terminates adjacent the shoulder portion 29. It will be 10 obvious that the interpositioning of the single gusset plate 30 between the upper flanges of the diaphragm members and the center sill reinforcing sills serves to provide a connection of relatively light weight and maximum strength value.

The diaphragm members are each provided with lower outwardly extending flanges 32, said flanges being connected to the respective gusset plates 33 by means of 20 rivets 34. The flanges 32 conform to the incline or taper of the web portion of the diaphragm members and extend throughout the bottom edge thereof. Each gusset plate 33 is provided with an inwardly extending 25 portion 35, said inwardly extending portion extending throughout the length thereof. The forward end of each gusset plate 33 is connected by means of rivets 36 to the lower flange of the bolster, said gusset plate being 30 interposed between the bottom flange 32 and the uppermost face of the lower bolster flange 3. The rear portion of each gusset plate 33 underlies the shoulder portion 29 of the upper diaphragm flange 27 and is adapted 35 to extend beyond said shoulder portion and be connected to the underface of the center sill reinforcing members by means of rivets 37.

The diaphragm members are preferably 40 positioned out of longitudinal alinement with respect to the draft sills, the inwardly extending flanges 27 of the diaphragm members being preferably in longitudinal alinement with the outwardly projecting horizontal flanges of the members 6 and 7 forming the draft sills.

An underframe for railway cars constructed in accordance with my present invention provides a relatively light weight 50 structure intimately associated with the bolster and capable of being readily and inexpensively assembled. It will also be obvious that the backstop member is effectively reinforced so as to receive the buffing loads, 55 the reinforcing means being adapted to transmit to the car sills the buffing loads at points where the latter are best able to withstand the excessive strains.

In addition it will be seen that an underframe is conveniently provided for older 60 types of cars wherein modern draft rigging equipment can be easily installed.

I claim:

1. In a car underframe, the combination 65 with center sills and bolster, of center sill

reinforcing members adapted to be connected to said center sills, draft sills having their inner ends connected to the bolster, diaphragm means connected to said center sill reinforcing members at the rear of the bolster, and a gusset plate interposed between and connected to said bolster and center sill reinforcing members. 70

2. In a car underframe, the combination with center sills and bolster, of center sill 75 reinforcing members connected to said center sills and overlying the bolster, draft sills having their inner ends connected to the bolster, diaphragm means extending rearwardly of the bolster and underlying the center sill reinforcing members, said diaphragm means being arranged in alinement with said draft sills, and a pair of gusset plates connecting said diaphragm means to the bolster and center sill reinforcing members. 80

3. In a car underframe, the combination with car sills and bolster, of reinforcing members adapted to be connected to said car sills, draft sills, means connecting the inner 85 ends of said draft sills to the bolster, gusset plates interposed between and connecting the draft sills to the bolster forwardly thereof, diaphragm means having a portion connected to the means connecting the inner 90 ends of the draft sills to the bolster, and means including a gusset plate interposed between and connecting the diaphragm means to said bolster. 95

4. In a car underframe, the combination with center sills and bolster, of center sill 100 reinforcing members connected to said center sills, draft sills arranged beneath the center sills and reinforcing members, means including gusset plates connecting the inner 105 ends of said draft sills to the bolster, diaphragm means located at the rear of the bolster, and means including gusset plates connecting said diaphragm means to said bolster. 110

5. In a car underframe, the combination with center sills and bolster, of center sill 115 reinforcing angle members connected to said center sills, angle iron draft sills arranged beneath the center sills and connected to said reinforcing members, diaphragm means arranged at the rear of the bolster and disposed in alinement with the draft sills, and means connecting the inner ends of said draft sills and forward ends of said diaphragm means to the bolster. 120

6. In a car underframe, the combination with car sills and bolster, of reinforcing members adapted to be connected to said car sills, draft sills formed with outwardly 125 extending upper and lower flanges, gusset plates interposed between and adapted to connect said lower flanges of the draft sills to the bolster, diaphragm members each having upper and lower flanges, the upper 130

flange of each diaphragm member being connected to an adjacent car sills reinforcing member, and a gusset plate adapted to unite the lower flange of each of said diaphragm members with the bolster.

7. In a car underframe, the combination with center sills and bolster, of center sill reinforcing members adapted to be connected to said center sills and arranged to overlie the boiler, draft sills formed with outwardly extending flanges, gusset plates interposed between and adapted to connect said flanges of the draft sills to the bolster, flanged diaphragm members having their upper portions connected to an adjacent center sill reinforcing member at the rear of the bolster, and a gusset plate interposed between said flanged diaphragm members and the center sill reinforcing members, said gusset plate being connected to and adapted to overlie said bolster.

8. In a car underframe, the combination with center sills and bolster, of center sill reinforcing members connected to said center sills, draft sills arranged beneath said center sills and reinforcing members, means connecting the inner ends of said draft sills to the forward portion of the bolster, reinforcing diaphragm members at the rear of the bolster, said diaphragm members being increased from a relatively small cross sectional area to a relatively large cross sectional area immediately adjacent the rear of the bolster, and a gusset plate interposed between said diaphragm members and center sill reinforcing members, said gusset plate being adapted to bridge said diaphragm members and arranged to overlie the bolster.

9. In a car underframe, the combination with center sills and bolster, of center sill reinforcing members connected to said center sills, draft sills arranged beneath the center sills and reinforcing members, means connecting said draft sills to the bolster, diaphragm members located at the rear of the bolster and connected to said center sill reinforcing members, each of said diaphragm members being provided with a cutaway portion, and a gusset plate positioned in the cut-away portions and bridging said diaphragm members, said gusset plate being connected to the bolster.

10. In a car underframe, the combination with center sills and bolster, of center sill reinforcing members connected to said center sills, draft sills arranged beneath the center sills and reinforcing members, means connecting said draft sills to the bolster, flanged diaphragm members provided at the rear of the bolster, a gusset plate interposed between and connecting the upper flanges of said diaphragm members to the center sill reinforcing members, and a gusset plate connecting the lower flange of each diaphragm member to the bolster.

11. In a car underframe, the combination with center sills and bolster, of center sill reinforcing members connected to said center sills, draft sills formed of a plurality of angle members, the horizontal flange of one of said angle members being connected to an adjacent center sill reinforcing member, and reinforcing diaphragm members provided at the rear of the bolster, each of said diaphragm members being provided with a horizontal flange arranged in longitudinal alignment with the horizontal flange of the other angle member forming the draft sill.

12. In a car underframe, the combination with center sills and bolster, of center sill reinforcing members connected to said center sills, draft sills formed of a plurality of angle members, a back stop connected to the vertical flanges of said angle members, and diaphragm members connected to said center sill reinforcing members and bolster at the rear thereof, each of said diaphragm members including a flange arranged in longitudinal alignment with a horizontal flange of one of said angle members forming the draft sill.

13. In a car underframe, the combination with center sills and bolster, of center sill reinforcing members adapted to be connected to said center sills, draft sills having their inner ends connected to the bolster diaphragm means including spaced members having their forward ends connected to the bolster and provided at their rear ends with a shouldered portion, means uniting the diaphragm members to the center sill reinforcing members, said means including a gusset plate adjacent said shouldered portion, and another gusset plate underlying said shouldered portion and adapted to be connected to the diaphragm member, bolster, and an adjacent center sill reinforcing member.

14. In a car underframe, the combination with center sills and bolster, of center sill reinforcing members adapted to be connected to said center sills, draft sills having their inner ends connected to the bolster, diaphragm means including spaced members having their forward ends connected to the bolster and provided at their rear ends with a shouldered portion, and means including a gusset plate interposed between the center sill reinforcing members and diaphragm members, said gusset plate being adapted to bridge the same and having its rear end adjacent said shouldered portion.

15. In a car underframe, the combination with center sills and bolster, of center sill reinforcing members connected to said center sills, draft sills formed of a plurality of angle members having their vertical flanges riveted together, a back stop member interposed between said draft sills and connected thereto by means of the rivets uniting the vertical flanges of said angle members, and

means arranged at the rear of the bolster and connected to the center sill reinforcing members for bracing said draft sills.

16. In a car underframe, the combination 5 with center sills and bolster, of center sill reinforcing members connected to said center sills, draft sills arranged beneath the center sills and reinforcing members, means connecting the inner ends of said draft sills 10 to the bolster, a back stop adapted to be engaged by a movable element of the draft rigging, a tie plate connecting the draft sills and arranged intermediate the ends of the back stop, and gusset plates connected to 15 said tie plate, draft sills, and bolster, said gusset plates extending forwardly substantially the length of said back stop.

17. In a draft rigging, the combination with center sills and bolster, of a movable 20 draft rigging element, draft sills, means connecting the inner ends of said draft sills to said bolster, a back stop member interposed between and connected to said draft sills, said back stop member being adapted 25 to contact the movable draft rigging element, gusset plates connecting said draft sills to the bolster, diaphragm means arranged at the rear of said bolster, and gusset plates connecting said diaphragm members to the 30 bolster.

18. In a draft rigging, the combination with center sills and bolster, of a movable draft rigging element, draft sills, means connecting the inner ends of said draft sills to 35 said bolster, a back stop member interposed between and connected to said draft sills, said back stop member being adapted to contact the movable draft rigging element and means including reinforcing diaphragm members having flanged portions arranged 40 in longitudinal alignment with said draft sills, said diaphragm members being arranged at the rear of the bolster and connected thereto.

19. In a draft rigging, the combination 45 with center sills and bolster, of a movable draft rigging element, draft sills, means connecting the inner ends of said draft sills to said bolster, a back stop member adapted to contact the movable draft rigging element, 50 said back stop member being interposed between and connected to said draft sills, and means including a gusset plate connecting said draft sills and bolster, said gusset plate extending forwardly of the rear of said back 55 stop.

In testimony whereof, I affix my signature.

DONALD S. BARROWS.
